UNITED STATES PATENT OFFICE

MORRIS KIND, OF BRYN MAWR, PENNSYLVANIA, ASSIGNOR TO HERCULES CEMENT CORPORATION, OF PHILADELPHIA, PENNSYLVANIA, A CORPORATION OF PENNSYLVANIA

CAR FOR TRANSPORTING CEMENT OR THE LIKE

Application filed October 12, 1928. Serial No. 312,269.

This invention relates to a car particularly adapted for transportation of cement or the like in bulk.

In order to transport cement in bulk in a satisfactory manner it is necessary to protect the same from moisture and it is further necessary to provide for ready removal thereof from the bottom of the car in which it is contained. As cement or similar heavy material is removed from a car which is supported through the medium of springs, the car will rise due to the lightening of the load and accordingly it is necessary to provide means permitting proper unloading irrespective of the upward movement of the car.

It is the broad object of the present invention to provide a railroad car which may be readily loaded and discharged and which will be substantially water-tight to prevent injury to a material such as cement in bulk when the same is in transit. It is a further object of the invention to provide means whereby a suitable discharge may be effected.

Further more detailed objects of the invention and their accomplishment will be apparent from the following description read in conjunction with the accompanying drawings, in which:

Fig. 1 is a longitudinal section through one end of the improved car.

Fig. 2 is a horizontal section through an end of the improved car.

Fig. 3 is a vertical section through the centers of opposite hoppers.

Fig. 4 is a detail section view showing the discharging means for the car.

The car comprises a longitudinal draft beam 2 running its full length, to the ends of which are secured suitable couplings 4 in the usual manner. The draft beam is mounted as indicated at 6 upon suitable trucks (not shown) provided with wheels 8. This mounting may be of the usual form in which springs are provided to take up the shocks incident to transportation.

Suitably supported from the draft beam is the body proper of the car which comprises upright side walls 10 surmounted by a roof 12, the central portion of which is provided with openings 14 adapted for charging,

which openings are, during transportation, covered by removable covers 16 which are adapted to be clamped down over the openings to secure against the entrance of rain or moisture. Inasmuch as openings 14 extend along the center of the car the usual runway may be provided at one side thereof, as indicated at 18.

At the bottom of the car are provided a series of hoppers designated generally by the numeral 20 which open on opposite sides of the draft beam, being arranged in pairs the members of which are opposite each other. In the car shown there are eight of these hoppers, four being arranged on either side of the draft beam. Each hopper is of general pyramidal formation having inner walls 22, which walls 22 of opposite hoppers meet to form a ridge extending longitudinally of the car. As shown in Fig. 2, the walls of the various hoppers are so arranged that the ridge formed by the junction of walls 22 is substantially continuous through the length of the body.

The outer walls of the hoppers are formed by sloping wall members 24 secured at their upper ends to the side walls 10. Between adjacent hoppers, arranged longitudinally of the car, are walls 26, the adjacent ones of which meet to form transverse ridges extending crosswise of the car. The end walls of the end hoppers are formed by the sloping end walls 28 of the car which form continuations into the hoppers, as shown in Fig. 1. In order to properly brace the various sections, angular flanges 30 may be provided for securing the upper portions of the hopper walls to the sides of the car.

By the arrangement described, it will be noted that the car may be readily filled through openings 16, each of which is disposed in approximate alignment with the members of a transverse pair of hoppers and in a position directly above the ridge formed by the meeting upper edges of sides 22. By this means a charge of cement or the like entering through the openings may completely and evenly fill the car. Upon opening of the bottoms of hoppers 20 in a manner to be hereafter described the cement is free to flow

completely through the hoppers from the car, since there are no horizontal platforms or the like within the car, all of the walls tapering toward some one of the hoppers.

Surrounding the bottom of each hopper 20, as shown in Fig. 4, is a suitable frame 32 within which is slidably mounted a gate 34 arranged to move horizontally across the mouth of the hopper to close the same. In order to insure complete closure of the hopper bottom during transit in a more secure manner than may be attained through the use of gate 34 there is provided a cover 36 pivoted at 38 to frame 32, which cover is arranged to engage over the periphery of frame 32 to completely close the bottom of the hopper and enclose the gate 34. In order to secure the cover in position a latch member 40 is adapted to be moved over the flange 42 of the frame where it may be secured by a pin passed transversely through suitable aligning holes 44 in the frame.

To secure a discharge of the car without permitting a loss of the contents or admixture thereof with water in case of a very moist atmosphere or rain, a flexible tube 46 formed of duck or canvas may be provided. This tube is secured at its upper end to a frame 48 and at its lower end to a similar frame 52. The center portion of the tube is held in expanded condition by means of a metallic ring or the like 50 which prevents its collapse when in use. Frame 52 is secured to a plate 54, which may be detachably held upon the top of a conveyor box 56 by means of spring clamps 58. The upper end of the flexible tube 46 with the frame 48 is preferably made so as to be readily detached after an unloading operation is completed.

As indicated in Fig. 4, when the car is full, the tube will occupy the position shown at 46', by reason of the fact that the car at this time, being loaded, compresses the springs and the body is accordingly in a lower position. As discharge takes place through tube 46, the cement passes into the conveyor 56 and is moved to a suitable storage or mixing place by a screw conveyor or the like 60. As the discharge proceeds, the body rises upon the springs and consequently tube 46 finally reaches the position indicated in full lines in Fig. 4. The utility of the flexible connection will accordingly be seen to reside not only in the ease of handling and the protection afforded to the discharge, but also in its automatically providing for the rise in the car occasioned by its discharge.

By the arrangement of the hoppers to discharge on opposite sides of the draft beam it will be seen that there is provided a car in which none of the contents will be held so that the discharge would be incomplete. The advantages of having a draft beam extending the complete length of the car are re-

tained together with the accomplishment of complete discharge.

What I claim and desire to protect by Letters Patent is:

1. A car comprising a frame including a longitudinally extending draft beam, a body mounted on said frame including side and end walls, and hoppers extending downwardly on opposite sides of the draft beam, said hoppers having bottom discharge openings with closure means therefor and having inner and outer walls, the inner walls of adjacent hoppers meeting in a ridge extending longitudinally of the car above the draft beam and extending to said openings, and the outer walls extending from the side walls of the body to the openings, the outer walls of the hoppers being inclined at larger angles to the horizontal than the inner walls of the hoppers whereby the openings are located adjacent the sides of the car body. 75

2. A car comprising a frame including a longitudinally extending draft beam, a body mounted on said frame including side and end walls, and hoppers extending downwardly on opposite sides of the draft beam, said hoppers having bottom discharge openings with closure means therefor and having inner and outer walls, the inner walls of adjacent hoppers meeting in a ridge extending longitudinally of the car above the draft beam and extending to said openings, and the outer walls extending from the side walls of the body to the openings, the adjacent hoppers on each side of the car having end walls meeting in transverse ridges, the outer walls of the hoppers being inclined at larger angles to the horizontal than the inner walls of the hoppers whereby the openings are located adjacent the sides of the car body. 100

3. A spring supported car for handling cement or like material in bulk including a frame having a longitudinally extending draft beam, a body mounted on said frame, and hoppers extending downwardly on opposite sides of the draft beam, said hoppers having discharge openings with closure means therefor, the inner walls of adjacent hoppers meeting in a substantially central, longitudinal ridge and extending to said openings, and the outer walls of said hoppers being inclined at larger angles to the horizontal than the inner walls whereby the discharge openings are located adjacent the sides of the car body. 115

In testimony of which invention, I have hereunto set my hand, at Philadelphia, Pennsylvania, on this 11th day of October, 1928.

MORRIS KIND.
